UNITED STATES PATENT OFFICE.

CHARLES E. J. LANG AND MICHAEL W. GAFFNEY, OF CLEVELAND, OHIO, ASSIGNEES
TO THE RAUCH & LANG CARRIAGE COMPANY, OF CLEVELAND, OHIO, A CORPOR-
ATION OF OHIO.

DESIGN FOR A VEHICLE-BODY.

41,038.

Specification for Design.

Patented Dec. 13, 1910.

Application filed October 15, 1910. Serial No. 587,327. Term of patent 7 years.

To all whom it may concern:

Be it known that we, CHARLES E. J. LANG and MICHAEL W. GAFFNEY, citizens of the United States, and residents of Cleveland, county of Cuyahoga, and State of Ohio, have jointly invented a new, original, and ornamental Design for Vehicle-Bodies, of which the following is a specification, reference being had to the accompanying drawing, forming part thereof.

In said annexed drawing:—Figures 1 and

2 are perspective views of a vehicle body, showing our new and ornamental design.

We claim:—

The ornamental design for a vehicle body, as shown.

Signed by us this 5th day of October, 1910.

CHAS. E. J. LANG.
MICHAEL W. GAFFNEY.
